UNITED STATES PATENT OFFICE.

BRONISLAW AMBROSIEWICZ, OF HAMTRAMCK, MICHIGAN.

DESIGN FOR A SEWING-MACHINE ARM.

58,420.

Specification for Design.

Patented July 19, 1921.

Application filed July 9, 1920. Serial No. 395,152. Term of patent 14 years.

To all whom it may concern:

Be it known that I, BRONISLAW AMBROSIEWICZ, a citizen of Poland, and a resident of Hamtramck, in the county of Wayne and State of Michigan, have invented a new, original, and ornamental Design for a Sewing-Machine Arm, of which the following is a specification, reference being

had to the accompanying drawing, forming part thereof.

The figure is a front view of a sewing machine arm showing my new design.

I claim—

The ornamental design for a sewing machine arm as shown.

BRONISLAW AMBROSIEWICZ.
